ss. *John Donovan*

UNITED STATES PATENT OFFICE.

JEROME LLOYD, OF BRYN MAWR, PENNSYLVANIA.

SAND CAR.

Application filed June 13, 1925. Serial No. 36,906.

This invention relates to improvements in freight cars of the closed or box car type, an object being to provide a car of this character which is adapted to carry sand or other loose material, with means for dumping the material to one side of the car.

Another object of the invention is the provision of means for controlling the dumping operation from the outside of the car and without opening the car door.

Another object of the invention is the provision of means for opening and closing the car door and for holding the door in closed position, novel means being provided for operating the door holding means.

With the above and other objects in view, the invention further includes the following novel features and details of construction, to be hereinafter more fully described, illustrated in the accompanying drawings and pointed out in the appended claims.

In the drawings:-

Figure 1 is a side elevation of a car constructed in accordance with the invention.

Figure 2 is a section on the line 2—2 of Figure 1.

Figure 3 is a fragmentary section on the line 3—3 of Figure 2.

Figure 4 is a section on the line 4—4 of Figure 3.

Figure 5 is a similar view on the line 5—5 of Figure 3.

Referring to the drawings in detail wherein like characters of reference denote corresponding parts, the reference character 10 indicates a closed freight car which may be of any suitable construction and which is provided at opposite sides with doors 11 and at opposite ends with discharge openings 12, the latter being located in the bottom or floor of the car.

Slidably mounted within the openings 12 as shown at 13 in Figure 3 of the drawings are closures 14, while located beneath these openings for the reception of material passing therethrough, are chutes 15. These chutes incline downwardly and inwardly toward the center of the car and are provided at their inner ends with discharge openings 16. These openings 16 discharge into an inclined trough or chute 17 which is located centrally beneath and extends transversely of the car. The trough or chute 17 is open at its outer end so that material from the

car may pass through the openings 12 and

be conveyed by the chutes 15 to the chute 17 and outward to one side of the car.

Secured to the closures 14 are racks 18 and the latter are engaged by pinions 19 which are secured to the inner ends of shafts 20. These shafts are mounted in suitable bearings 21 and extend longitudinally of the car toward the opposite ends being provided with crank handles 21' at their outer ends so that the shafts may be rotated. By this means, the closures 14 may be moved within the guide 13 to open or close the openings 12.

Each of the doors 11 has secured thereto a rack 22 and these racks are engaged by pinions 23 which are operated by crank arms 24. By means of the arms 24, the pinions 23 may be operated to open and close the doors 11.

Each of the doors 11 has secured thereto spaced keepers 25 which are adapted to be engaged by latches 26, the latter being pivotally mounted as indicated at 27 upon the side of the car. The latches 26 are movable in guides 28 and are connected by a link 29 so as to provide for their simultaneous pivotal movement. One latch of each side of the car carries an angularly extending arm 30 and this arm is secured by means of a pivoted link 31 to one end of a rack bar 32. This bar operates within a guide frame 33 secured to the side of the car and is engaged by a pinion 34 which is operated by a crank arm 35. Guide pinions 36 also engage the rack bar to provide smoothness of operation.

The crank arms 24 and 35 are removable and these arms are adapted to be placed within suitable recesses formed in the sides of the car and normally closed by substantially L-shaped plates or covers 36.

By means of the crank arm 35, the latches 26 may be simultaneously operated to release them from the keepers 25, whereupon the crank arm 24 may be rotated to open the door 11.

The invention is susceptible of various changes in its form, proportions and minor details of construction and the right is herein reserved to make such changes as properly fall within the scope of the appended claims.

Having described the invention what is claimed is:-

1. A car having an opening in the bottom thereof, an inclined chute located transversely beneath the bottom of the car, an in-

clined chute located beneath the opening and extending longitudinally of the car above the transverse chute, a sliding closure for the opening and means to operate the closure.

2. A car having an opening in the bottom thereof, an inclined chute located transversely beneath the bottom of the car, an inclined chute located beneath the opening and 10 extending longitudinally of the car above the transverse chute, a sliding closure for the opening, a rack secured to the bottom of the closure, a shaft journaled beneath the car, a pinion secured upon one end of the 15 shaft and engaging the rack and means at the opposite end of the shaft to rotate the latter and operate the closure.

3. A car having spaced openings in the bottom thereof, an inclined chute extending 20 transversely of the bottom of the car between

the openings, an inclined chute located beneath each opening and extending longitudinally of the car above and emptying into the transverse chute, a sliding closure for each opening and means to operate the closures. 25

4. A car having a flat bottom and an opening in said bottom adjacent each end of the car, a horizontally and laterally movable slidingly mounted closure for each opening, a transversely inclined chute located beneath the car between the openings, said chute opening at one side of the car, a longitudinally inclined chute located beneath each opening at each end of and discharging into the transversely inclined chute and means associated with each closure and 30 extending outward to operate the closures. 35

In testimony whereof I affix my signature.
JEROME LLOYD.
